UNITED STATES PATENT OFFICE.

JACOB WALTER BERKOF, OF NEW YORK, N. Y.

DESIGN FOR A TOY ANGORA POODLE-DOG.

42,497.

Specification for Design.

Patented May 14, 1912.

Application filed December 18, 1911. Serial No. 666,611. Term of patent 7 years.

To all whom it may concern:

Be it known that I, JACOB WALTER BERKOF, a citizen of the United States, residing in the city of New York, borough of Brooklyn, in the county of Kings and State of New York, have invented a new, original, and ornamental Design for a Toy Angora Poodle-Dog, of which the following is a specification, reference being had to the accompanying drawing, forming part thereof.

The figure is a front elevation of the toy partly in perspective, showing my new design.

I claim:

The ornamental design for a toy Angora poodle dog, as shown.

JACOB WALTER BERKOF.

Witnesses:

W. S. ORTON,

PHILIP D. ROLLHAUS.
